PALEMON H. GASKINS, OF JACKSONVILLE, FLORIDA.

CIRCULATING SYSTEM FOR INTERNAL-COMBUSTION ENGINES.

Application filed February 11, 1922. Serial No. 585,856.

To all whom it may concern:

Be it known that I, PALEMON H. GASKINS, a citizen of the United States, and a resident of Jacksonville, in the county of 5 Duval and State of Florida, have invented certain new and useful Improvements in Circulating Systems for Internal-Combustion Engines, of which the following is a specification.

10 This invention relates to internal combustion engines and more particularly to a circulating system therefor in which water, or the like, is employed as a cooling medium.

The object of the invention is to provide 15 a circulating system of the above character adapted to permit the liquid employed as a cooling medium to be used when heated to a high degree by the heat generated in the associated engine; and with a minimum loss 20 of the cooling medium by evaporation or otherwise.

Other objects will hereinafter appear in the detailed description to follow.

The invention is illustrated by way of 25 example in the accompanying drawing, in which the figure represents a sectional perspective view of the forward portion of an automobile and showing the application of the present invention.

30 Referring to the drawings more particularly, E indicates generally an engine which in this instance is cast en bloc, although it is to be understood that my invention may be applied to other types of engines. The engine E has its cylinder surrounded by the usual cooling or water jacket W and which 35 communicates with the manifold M which is mounted upon said jacket. At K is indicated a radiator which is provided with the usual cap C threaded upon the neck 10 of the radiator. Also at 11 there is indicated the usual drain tube, the upper end of which is disposed within the neck 10 and its lower end brought to a position for dis- 40 charging water or steam therefrom without injuring parts of the automobile. The radiator has extending from its upper end a nipple 12 and from its lower end a nipple 13, said nipples, in each instance, communicating with the interior of the radiator casting in the usual manner.

In the present instance, the free end of the manifold M is connected through a flexible tube or hose 14 with the radiator nipple 13. The cooling or water jacket W of the engine E has also secured thereto an elbow 45

15 which communicates with the interior of the water jacket at its one end and at its other end with a pump P. The pump P is preferably of the rotary type and driven by 50 a shaft 3, said shaft in turn carrying upon its forward end a suitable pulley over which may pass a belt 16, whereby the shaft S may be driven from the crank shaft of the associated engine E. The shaft S may 55 be the usual means for driving the radiator fan of the automobile and simply extended to drive the pump P. The fan is driven by the belt 18 and the pulley 17. The extended portion of the shaft S for the pump may 60 be journaled by suitable bracket bearings 19.

The inlet of the pump P communicates with the one end of a hose 20, the other end of the hose communicating with the interior of the radiator R through the nipple 12. The hose 20 may be secured to the nipple 12 and to the inlet nozzle or nipple of the pump P by any conventional means, and also the hose 14 may have its ends secured to 75 the manifold M and radiator nipple 13 in any suitable manner.

At a point adjacent the forward end of the manifold M there is threaded therethrough the one end of a tube 21 which is 80 preferably of the diameter shown, and the other end of said tube is connected with the radiator R at approximately the point 22. The tube 21 establishes communication between the manifold and the interior of the 85 radiator at the points mentioned.

The operation of the present circulating system is as follows: The water or other cooling medium within the radiator R passes downwardly through the hose 20 as indicated by 90 the arrows 23 and is forced into the cooling jacket W of the engine E by the pump P and from thence through the manifold M, hose 14, and into the lower end of the radiator R. The water proceeds upwardly 95 through the radiator and is thus cooled. By providing a pump for forcing the water or other cooling medium through the cooling jacket of the engine insures that a circulation will always be had. Any steam which 100 may be generated in the cooling jacket W and carried into the lower part of the radiator through the hose 14 will be entirely condensed or dissipated before it reaches the upper portion of the radiator and thus insure that a minimum quantity of the cooling 105 medium will escape to the drain tube 11.

As stated in the objects of the present invention, the present circulating system permits the water or other cooling medium to reach a high degree of temperature and yet be utilized with certain advantages. As is well known an engine will operate at its highest efficiency when its engine walls are retained hot, but not to an excessive degree. If the water or other cooling medium was at 10 its boiling point and steam could circulate without harmful results the engine would operate at its best efficiency. In this instance when the water is brought to its boiling point, or above, steam will of course be generated and as the water is passing from the manifold M the pressure of steam is relieved by the tube 21. The steam passing through tube 21 will enter the radiator at a point beneath the water therein and will circulate upwardly to the water and before 20 reaching the nipple 12 will be mostly condensed or dissipated and thus will not cause an overflow through the drain tube 11.

I claim:

In a circulating cooling system for internal combustion engines, a radiator, a cooling jacket for the cylinder of the engine, a connection between the outlet of the cooling jacket and the bottom of the radiator, a connection between the inlet of the water jacket 25 and the top of the radiator, and a bypass connection between the outlet of the cooling jacket and the radiator, said bypass communicating with the radiator at a point below the outlet thereof.

PALEMON H. GASKINS.
